(57) **CLAIM**

The ornamental design for a pot lid, as shown and described.

DESCRIPTION

FIG. 1 is a first perspective view of a pot lid showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the pot lid shown in use.

The broken lines shown in the drawings depict environment and portions of the pot lid that form no part of the claimed design.

1 Claim, 9 Drawing Sheets
